STAND BOILER WITH VERTICAL FIRE TUBES
AND HORIZONTAL WATER BAFFLES

Samuel J. Jacoby, St. Louis, Mo.

Application January 2, 1951, Serial No. 203,945

1 Claim. (Cl. 122—17)

1

This invention relates to improvements in water heaters, and more particularly to an arrangement of elements in a storage-type heater conducing to greater thermal efficiency, a considerably more even temperature throughout the body of heated water, a minimal loss of heat value and lessened inconvenience due to formation of steam pockets and the like within the tank of the heater.

Storage-type water heaters are prevalently utilized in vast numbers to provide a supply of hot water for personal, laundry and other usage, both in domestic and commercial installations. The present preference by the trade for water heaters of so-called high recovery rate, accentuates the problem to be described and particularly enhances the value of the present improvements. The problem solved by present improvements results from the tendency of extremely hot water and in many cases steam, to rise along the one or more flues or flue tubes within the tank of the heater. This rapidly rising, relatively highly heated fluid many times results in formation of steam in the upper portion of the storage tank long prior to such time as the sensing element of the thermostat within the tank, calls for a reduction or cessation of heat from the source thereof. The situation described is obviously wasteful and inefficient, and since in many cases the hot water is drawn from the upper portion of the tank, there results an outflow of steam or under certain conditions excessively hot water. The present improvements accordingly have as their principal and major objectives, the elimination of the shortcomings aforesaid, and the general improvement of efficiency of water heaters of storage tank type.

Yet another object of the invention is realized in an improved arrangement of flue tubes and baffle elements associated therewith, such as to result in a virtually complete and thorough admixture of the heated with the preheated water in a storage tank heater, as the heated water rises through the body of that in storage, thus conducing to a virtually even temperature of the warmed body of water in all parts of the tank.

A still further and important objective of the present improvements is realized in an improved arrangement of flue tubes and water baffles, and an optimum arrangement and location of the sensing element of a thermostat utilized with such an assembly, to obviate the difficulties first above noted.

The foregoing and numerous other objects and advantages will more clearly appear from the fol-

2

lowing detailed description of a currently preferred embodiment, particularly when considered in connection with the accompanying drawing, in which:

5 Fig. 1 is a vertical sectional elevation taken in an axial plane of a vertical water storage heater;

Fig. 2 is a horizontal sectional view as taken along line 2—2 of Fig. 1;

Fig. 3 is a horizontal sectional view as taken along line 3—3 of Fig. 1, and

Fig. 4 is a horizontal sectional view as taken along line 4—4 of Fig. 1.

Referring now by characters of reference to the drawing, the tank proper includes an outer shell 15 OS and an inner shell IS, both shown in cylindrical form but without limitation to exact shape, and with the inner cylindrical wall spaced inside the outer sufficiently to provide a space therebetween for the accommodation of thermal insulation INS. The outer tank is provided with a convex upper closure UC and an upwardly convex, downwardly concave bottom closure or crown sheet CS at its lower end. Both of the end closures are suitably apertured conformably to and 20 in sealing relation with one or more vertical flues or flue tubes F. In the drawing these are shown in a plurality of four, in a symmetrical arrangement, and with the axes of the several flue tubes F substantially equidistantly located from the vertical axis of the tank. Below the tank and 25 particularly below the crown sheet CS, is a burner B for any suitable type of fuel, here shown as a gas burner provided with the usual automatic controls, valves, pilot and the like (not shown). The burner B is or may be, in well known manner, subject to an off-and-on control, or to a regulated throttling control of a thermostat generally indicated at T and characterized by an 30 enclosed sensing element SE which preferably is located about as shown in Figs. 2 and 4. The burner is supplied by a gas supply line GSL (Fig. 1) and the tank assembly, as is conventional, is supported somewhat above floor level as by legs L.

In the upper portion of the outer tank, closed 35 by a top cover TC, is a flue space FS whence the hot gases and production of combustion from the burner B directed upwardly through flues F are consolidated and directed outwardly through a pipe P to the usual chimney or stack. A water inlet connection IC and a hot water outlet connection OC, are or may be conventional and are 40 presently included for completeness of disclosure.

The embodiment of present improvements in a 45 preferred form, includes a vertical stack of 50 spaced baffles, preferably of sheet metal, the low-

ermost of the series of which is indicated at 10. For each of the flues F there is provided in the baffle 10 an aperture of a size snugly to fit and closely to embrace the adjacent flue tube, the number of such apertures corresponding, in baffle 10, to the number of tubes. The baffle 10 and other similar baffles, may be welded or otherwise fixedly attached to the flue tubes so as to be supported thereby, from which it will appear that any tendency of the one or more flue tubes to become bent or warped from thermal or other effects, from an original vertical linear position, and in a multiple flue unit, thus to be brought out of parallelism with the companion flues, is obviated by the bridging and bracing effect of the several baffles of the stack, such as 10 and others to be described. It will be noted as from Fig. 3, that the peripheral margin, or at least a substantial portion of such margin, is spaced from the nearest tank wall, being the inner cylindrical surface of the inside tank. This spacing as will appear, permits water circulation between marginal portions of the baffle, and the adjacent wall of the tank as the heated water moves upwardly.

It is a preference that the vertical spacing of adjacent baffles be at least such as to amount to two or three times the diameter of the individual tubes. The next adjacent baffle proceeding upwardly of the stack, and indicated at 11, is or may be similar in all respects as to structure and attachment, to the baffle 10, with the exception that baffle 11 is preferably provided in a multiple flue heater with a large central opening 12. The area of such opening and its location are such as to conduce to a flow of the heated water originally proximate to the tubes, in a direction radially inwardly of the tank, thence upwardly through the opening 12, thence impinging the next baffle of the series indicated at 10. Since this latter is imperforate except where traversed by the flue tubes, the heated water is again compelled to proceed to the free marginal portions of the baffle and so to move radially outwardly of the tank as it moves across the free margins of the next baffle 10.

The baffles 10 through the series are preferably intervened by the baffles 11 with a repetition of the circulatory and directive effects above described. Thus it will be seen that the column or columns of heated water warmed through the crown sheet CS and the several flue tubes F, will result in an inward, thence outward, thence inward movement of the water with respect to the axis of a vertical tank, as shown by the arrows (Fig. 1). Otherwise expressed, there results a zig-zag travel of the heated column or columns of water rising through the tank.

It is a preference that the first baffle 10 of the series be imperforate rather than perforate; similarly, that the uppermost baffle of the series 10 be imperforate, so as to supply the takeoff or upper portion of the tank, with water which has been subjected to an unusual extent of linear travel as same rises through the tank.

Numerous experiments have been made with different locations, in the present baffle and tube assembly, of the sensing element SE of the thermostat controlling the burner B. It has been found conducive to a more uniform water temperature throughout the tank to locate such a sensing element about as shown by Figs. 1 and 4, with the element SE extended radially and horizontally into the central or axis region of the tank, and so that the element SE is located about midway, vertically, between the first and

second baffles 10 and 11 proceeding from the bottom of the stack. While such location is by no means critical, it has been found highly advantageous as reflected in better heating efficiency and greater uniformity of water temperature throughout the tank.

It is preferred as a matter of simplicity of formation to construct each of the baffles 10 and 11 so that it conforms substantially in shape to the section of the water-confining wall of the tank, these elements being respectively circular and cylindrical but with the described spacing of the baffle margins inwardly of the tank wall. Obviously, if desired for structural or other reasons, restricted portions of the margin of the baffles may extend to the inner tank wall, and thus enhance the bridging and bracing functions of the baffle. Thus there are distinctly contemplated, but without limitation, the possibility of serrate or scalloped baffle margins or other desired formation thereof (not shown).

The present improvements probably exhibit their greatest operating advantages in a multiple flue type of automatic storage heater assembly; it will, however, be understood that the improvements are of considerable advantage when utilizing but a single central flue tube in which case as in the present, the alternate perforate baffles will be punched or otherwise apertured so that their circulatory apertures are remote from the flue and located in the present structure substantially inwardly of the outer margins of the baffle.

It will have appeared that irrespective of any reasonably high combustion rate of the burner B tending with present constructions to drive upwardly, a rapidly moving column of water and steam along the exposed metal surfaces of the several flue tubes, there will not, as prevalently, result a steam pocket at the top of the tank proper; in fact the lateral circulatory movement imparted to the upflowing heated water will serve to mix the heated water with the cool water from supply connection IC, as well as with the whole body of the water in the tank, thus preventing any flash steam formation and resulting, as has been proven, in an approximate uniformity of temperature through the tank. This result is further assured, and any appreciable cold water column avoided in the tank, by the utilization of a lowermost imperforate baffle plate 10. Such an arrangement provides, as clearly appears in Fig. 1, a tempering chamber separate from the space thereabove except for the annular space peripherally of the lower baffle. The incoming cold water supply, preferably directed transversely of this chamber across the warmest lengths of the tubes F, will quickly bring the supply liquid to desired temperature.

Although the invention has been described by detailed reference to the elements of a single preferred embodiment of the invention, the detail of description is to be understood solely in an informative, rather than in any restrictive sense, numerous variants being possible within the scope of the claim hereunto appended.

I claim as my invention:

In a storage type water heater characterized by a vertical tank, the tank consisting of double spaced walls and provided with thermal insulation between said walls, a crown sheet at the lower portion of the water-containing portion of the tank, a plurality of flue tubes extending through the crown sheet then vertically through the water storage space of the tank, a flue space provided above the flue tubes, an outer flue di-

rected from said flue space, water inlet and outlet connections to the water space of the heater, a series of vertically spaced substantially horizontal plates serving as baffles located in the water space of the tank, each of said baffles conforming substantially in shape to the section of the water-confining wall of the tank, but being appreciably spaced inwardly therefrom, and each apertured to receive and closely to embrace the several vertical flue tubes, the lowermost of the plates of said series being imperforate except for flue tube apertures therein, and providing with the crown sheet, a substantially closed, cold-water-tempering chamber open only peripherally of the lowermost plate into the storage space thereabove, the water inlet connection opening into the tempering chamber, the next superjacent baffle plate being provided with a central aperture equidistantly spaced from the several flue tubes and substantially remote therefrom, the remaining baffle plates of said stack being alternately imperforate and perforate as described, apart from flue openings therein, whereby to promote a circulation of heated water alternately toward the outside of the tank, then toward the interior of the tank, thus providing a zig-zag path of travel of heated water upwardly of the tank; the several flue tubes having their exterior surfaces within the tank directly exposed to the body of water therein, and a tank

thermostat having a sensing element extended inwardly of the tank to the axial region thereof, and vertically intermediate the lowermost and next superjacent baffle plates, the sensing element being responsive to the temperature of water immediately subsequent to its emission from the tempering chamber and immediately prior to its passage through the central aperture of the said superjacent baffle plate, whereby to contribute to better heating efficiency and greater uniformity of water temperature throughout the tank.
